AUTOMATIC PIPE-CUTTING MACHINE

Anton Briglia, Brooklyn, N. Y., assignor to Muray Dolgov, doing business under the firm name of United Pipe Nipple Company, Brooklyn, N. Y.

Application April 17, 1948, Serial No. 21,663

9 Claims. (Cl. 164—61)

1

My invention relates to a machine which semi automatically operates the cut off actuator mechanism to cut off or sever a length of pipe or the like into nipples, or short lengths of pipe which may be manually fed into the machine.

Among the purposes and objects of my invention are to provide a cut off actuator which may be set to semi automatically repeat the cut off operation.

Another object is to electrically control a hydraulically operated cut off actuator for a pipe cutting machine.

An object is to provide an electric control and liquid pressure pump and valves for operating the cut off actuator by a fluid-motor.

Still another object is to provide an electrically controlled hydraulic system in which the direction of flow of liquid is reversed by the mechanical operation of the cut off actuator.

An object is to provide a hydraulic system, electrically controlled, in which the time of repeating the cycle of cutting off nipples in sequence from a pipe may be adjusted to suit the speed of the person feeding the pipe to be cut.

I accomplish these and other objects by the construction herein described and shown in the drawings which form a part of my disclosure.

In the drawings:

Fig. 1 is an elevational view showing the hydraulic system and electric controls for actuating the pipe into the cutter.

Fig. 2 is an elevational view showing the cutter and machine in full lines and the pipe and a support in broken lines.

Fig. 3 is a diagrammatic view of the hydraulic system.

Figs. 4, 5, 6 and 7 are electric diagrams showing the positions of the switches and valve parts during a single cycle of the cut-off operation.

Similar reference characters refer to similar parts throughout the several views of the drawing and in the specification.

My invention is particularly suitable for actuating the pipe into high speed cutters which rotate the pipe while being severed. The pipe is pressed against the rotating cutter; being actuated upwardly by a head having rollers to permit the pipe to rotate. The cutter, motor which rotates it, and the head for moving the pipe into the cutter are well known. The valves and switches which control them and the solenoids which are used also may be purchased and need not be modified to suit my system in which they are used.

The fluid-motor and many of the other parts

2

need not be described in detail further than to illustrate the use to which they are put in carrying out their instant functions which in some respects are similar to the automatic pipe cutter set forth in my co-pending application for patent filed April 5, 1948 having Serial #18,985 which differs from the instant disclosure by having the cut off mechanism modified to co-act with the feed for advancing the pipe a predetermined distance to suit the length of the nipples being cut off all automatically.

I have not attempted to show all possible modifications which may be made but rather to describe the construction of a preferred embodiment of my invention in precise detail so that it may be more easily understood by one skilled in the art to which this invention pertains. Modifications may suggest themselves after a study of this, my disclosure.

20 The preciseness of the detailed description and the preciseness of the details in the drawings are not intended to limit the scope of my invention which is set forth in the appended claims.

25 Referring to the drawings, I have shown a cutter 1 rotatably mounted in the stand 2 and driven by the electric motor 3 which also drives a pump 4 by a belt or the like 5 which transmits motion to the pump from the pulley 6 secured to the armature shaft 7 of the motor to the pulley 8 secured to and driving the shaft 9 of the pump.

The hydraulic system may be readily followed by referring to Fig. 3 of the drawings. The pump 4 receives liquid from the reservoir 10 under pressure through the pipe 12 to the pipe through the pipe 14 and discharges liquid 13 through the relief valve 14 to the four way valve 15.

30 A bypass valve 16 is provided with a hand wheel 18 to regulate or relieve the pressure in the pipe 12 and to render the operation of the hydraulic system inoperative as it affects the movements of the fluid-motor which has a cylinder 17 and which is provided with the piston 18 and piston rod 19 which actuates the pipe 20 into the cutter.

The pipe 13 may provide liquid under pressure through the four way valve to the pipe 22 into the cylinder of the fluid-motor and against the face 23 of the piston to actuate the pipe to be cut 20 into the cutter or the four way valve 15 may retract the piston by connecting the pipe 22 to the pipe 21 and the pipe 13 to the pipe 24 to act against the face 25 of the piston; the four

55

way valve thus reverses the flow of liquid in the pipe 22 or when again moved reverses the flow of liquid in the pipe 24. The motion of the piston 18 is also reversed when the flow of liquid is reversed and the pipe, being cut, and roller head 33, which forces the pipe into the cutter, also are reversed in direction of motion by movement of the four way valve.

To raise the pipe into the cutter the piston rod 19 moves the crosshead 26 to which it is secured and the connecting rod 27 which swings the lever 28 which rotates the cam shaft 29 and the cam 30 which presses upon and moves the cam follower 31 vertically upward which raises the adjusting screw 32, roller head 33 and rollers 34 which support and press the pipe 20 against the cutter 1 until severed, whereupon the motion is reversed by the retraction of the piston rod as above described.

The crosshead 26 is provided with the cams 35 and 36 each provided with its respective adjusting screw 37 or 38 to move the cam in the direction of travel of the crosshead to change the relative time for operating the switch operators 39 or 40 which close the normally open switch 41 or open the normally closed switch 42; the adjusting screws thus change the length of stroke of the parts moved by the fluid-motor or its relative travel at each end of its stroke; in most cases cam 36 does not require adjustment.

The operation of the switches 41 and 42 to move the four way valve 15, may be followed by referring to the wiring diagrams, Figs. 4, 5, 6 and 7. In Fig. 4 the crosshead is shown as moving toward the switch 41, which is normally open, whereupon contact by the cam 35, which engages the operator 39, closes the switch 41 to move and to reverse the four way valve, the crosshead and piston 18.

The switch 41, when closed, as shown in Fig. 5, energizes the solenoid 43 which closes the switches 44, 45 and 46 which are moved by the manifold operator 47 which is connected to the solenoid. When the switches 45 and 46 are closed, the solenoid 48 is energized which overcomes the spring 49 to move the valve 15 to connect the pipe 13 to the pipe 24 to force the piston 18, crosshead 26, and the pipe 20 to be retracted away from the cutter 1. Liquid is exhausted from the fluid-motor through the pipes 22 and 21 from the fluid-motor cylinder 17 to the reservoir 10.

In Fig. 6 the crosshead is shown moving toward the normally closed switch 42, which, when the cam 36 touches the operator 40, is opened thereby deenergizing the solenoid 43 which in turn opens the switch 46 to deenergize the solenoid 48 and thus permit the spring to move the valve 15 to connect the pipe 13 to 22 and the pipe 24 to 21, as shown in Fig. 7, to force the piston 18, crosshead 26 and rollers 34 to again press the pipe 20 against the cutter to again sever a new length of pipe and to repeat the cycle of operations as above described.

The electrical connections to the switches 41 and 42 and to the solenoid 48 for operating the four way valve are carried in the cables 50 from the boxes 51, one of which houses the solenoid 43, switches 44, 45 and 46. The boxes are preferably mounted on a panel 52 which is preferably secured to and supported by the motor and stand 2.

The pump 4, reservoir 10, fluid-motor 17, switches 41 and 42, the crosshead 26 and cams

35 and 36, relief valve 14 and bypass valve 16 are preferably mounted on the frame 53 which also supports the guides 54 for the crosshead. The frame is secured to or formed integral with the stand 2 which also is secured to the stop 55 which may be set to determine the length of the nipple being cut from the pipe 20 which contacts the stop when fed into the machine. The stop may be adjusted to suit the diameter of pipe being cut as well as the length of the nipple and is swingingly supported by the arm 56 which is clamped onto the stand 57 which is secured to the stand 2.

The term fluid-motor, as used herein, is intended to broadly include the cylinder, piston and such other parts which are used to impart motion to the parts above described in cutting the pipe into nipples in sequence; the fluid-motor thus moving its parts first in one direction, then in the opposite direction. The fluid-motor thus is broadly adapted to move the cams which operate the switches, solenoids, valve and other parts which are moved by pressure applied to the fluid-motor. The adjustment of the position of the cams in relation to the crosshead moved by the fluid-motor is directly capable of lengthening or shortening the stroke at each end or both ends of travel of the fluid-motor; the piston of which is responsible for its motion, the piston rod for its imparting motion and cylinder for its being able to convert pressure to the moving parts, all of these are broadly termed fluid-motor.

The material used and the size of the parts as well as the particular type and construction of the devices which may be purchased on the open market may vary without departing from the principles which underly my invention.

Having thus described a preferred embodiment of my invention what I claim as new and desire to secure by Letters Patent is set forth in the claims which follow.

I claim:

1. In a nipple cutting machine for automatically severing a pipe in sequence until cut into nipples, a pressure operated liquid-motor, a cutter and electric switch operating means moved by said liquid-motor to close and open said switches at each end of travel, said liquid-motor pressing said pipe into said cutter and withdrawing said pipe after being severed, a valve for admitting pressure and for exhausting pressure to move said liquid-motor, and electric operating means controlled by said switches to move said valve to reverse the motion of said liquid-motor, said electric operating means comprising a manifold switch and solenoid operating means for moving said manifold switch.

2. In a nipple cutting machine for automatically severing a pipe in sequence until cut into nipples, a pressure operated liquid-motor, a cutter and electric switch operating means moved by said liquid-motor to close and open said switches at each end of travel of said liquid-motor, said liquid-motor pressing said pipe into said cutter and withdrawing said pipe after being severed, a valve for admitting pressure and for exhausting pressure to move said liquid-motor, and electric operating means controlled by said switches to move said valve to reverse the motion of said liquid-motor, to again automatically repeat the cycle, said electric operating means comprising a manifold switch and solenoid operating means for moving said manifold switch and a solenoid for operating said valve.

3. In a nipple cutting machine for automatically

cally severing a pipe in sequence until cut into nipples, a pressure operated liquid-motor, a cutter and electric switch operating means moved by said liquid-motor to close and open said switches at each end of travel of said liquid-motor, said liquid-motor pressing said pipe into said cutter and withdrawing said pipe after being severed, a valve for admitting pressure and for exhausting pressure to move said liquid-motor, and electric operating means controlled by said switches to move said valve to reverse the motion of said liquid-motor, to again automatically repeat the cycle, said electric operating means comprising a manifold switch and solenoid operating means for moving said manifold switch and a solenoid for operating said valve, said solenoid being controlled by the operation of said manifold switch.

4. In an automatic pipe cutting machine having a rotary cutter and liquid pressure means for pressing the pipe being cut against the cutter to sever the pipe into nipples and electric switches and operators therefore to control said liquid pressure means to stop and reverse said liquid pressure means when said pipe has been severed, and to stop and reverse said liquid pressure means to again automatically repeat the cycle and to again press said pipe against said cutter to again sever said pipe whereby nipples may be intermittently severed in sequence in self repeating cycles until said pipe has been cut automatically into nipples.

5. In an automatic pipe cutting machine having a rotary cutter and liquid pressure means for pressing the pipe being cut against the cutter and electric switches and operators therefore to control said liquid pressure means to stop and reverse said liquid pressure means when said pipe has been severed and valve means and electric means to move said valve to stop and reverse said liquid pressure means at both extremes of travel and to again automatically repeat the cycle to continue the operating cycle until the length of pipe fed into the machine has been cut into nipples.

6. In a nipple cutting machine for automatically severing a pipe in sequence until cut into nipples, a pressure operated liquid-motor, a cutter and electric switch operating means moved by said liquid motor to close and open said switches at each end of travel of said liquid-motor, said liquid-motor pressing said pipe into said cutter and withdrawing said pipe after being severed, a valve for admitting pressure and for exhausting pressure to move said liquid-motor,

and electric operating means controlled by said switches to move said valve to reverse the motion of said liquid motor and to again automatically repeat the cycle.

7. In a nipple cutting machine for automatically severing a pipe in sequence until cut into nipples, a pressure operated liquid-motor a cutter and electric switch operating means moved by said liquid-motor to close and open said switches at each end of travel of said liquid-motor, said liquid-motor pressing said pipe into said cutter and withdrawing said pipe after being severed, a valve for admitting pressure and for exhausting pressure to move said liquid-motor, and electric operating means controlled by said switches to move said valve to reverse the motion of said liquid-motor and to again automatically repeat the cycle said switches comprising a normally open switch at one end of the stroke and a normally closed switch at the opposite end of the stroke of said liquid-motor.

8. In a nipple cutting machine for automatically severing the pipe in sequence until cut into nipples, a pressure operated liquid-motor and cutter and electric switch operating means moved by said liquid-motor to close and open said switches at each end of travel of said liquid-motor, electric operating means controlled by said switch and a valve operated by said electric operating means to change its direction of travel, to automatically and successively repeat the operating cycle.

9. In a nipple cutting machine for automatically severing the pipe in sequence until cut into nipples, a pressure operated liquid-motor and cutter and electric switch operating means moved by said liquid-motor to close and open said switches at each end of travel of said liquid-motor, electric operating means controlled by said switch and a valve operated by said electric operating means to change its direction of travel and to connect said valve to said liquid-motor to change its direction of travel and again automatically repeat the cycle to successively sever the pipe into nipples.

ANTON BRIGLIA.
